WILLARD G. COOK, OF PHILADELPHIA, PENNSYLVANIA, ASSIGNOR TO WESTINGHOUSE ELECTRIC & MANUFACTURING COMPANY, A CORPORATION OF PENNSYLVANIA

CONTROL SYSTEM

Application filed September 13, 1928. Serial No. 305,755.

My invention relates generally to relays, and more particularly to time element relays.

In the design and construction of relays, it is often desirable to provide for a long time element delay in the operation of the device. Heretofore the time element has been too short for a great many purposes and other expedients have been resorted to.

The object of the invention generally stated, is the provision of a time limit relay that shall be simple and efficient in operation and readily and economically manufactured.

A more specific object of the invention is to provide for increasing to a maximum, the period of time during which positive operation of an electromagnetic relay may be obtained at any predetermined time interval.

It is also an object of the invention to provide for the positive functioning of a relay at predetermined time intervals, without providing the relay with an air gap.

Other objects of the invention will, in part, be obvious and will, in part, appear herein-after.

The invention accordingly is disclosed in the embodiment thereof shown in the accompanying drawing and comprises the features of construction, combination of elements and arrangement of parts, which will be exemplified in the construction hereinafter set forth and the scope of the application of which will be indicated in the claims.

For a fuller understanding of the nature and objects of the invention, reference may be had to the following detailed description taken in conjunction with the accompanying drawing, in which:

Figure 1 is a view in side elevation of a relay constructed in accordance with this invention;

Fig. 2 is a front elevational view of the relay illustrated in Fig. 1;

Fig. 3 is a diagram illustrating how the relay may be connected into a circuit;

Fig. 4 shows a number of curves which demonstrate the characteristics possessed by a relay constructed in accordance with this invention, as compared with other types of relays;

Fig. 5 is a perspective view of a portion of the relay showing how the armature is mounted.

Referring now to the drawing, the relay illustrated comprises a frame 10, in which a core member 11 is mounted. The core member may be mounted in any suitable manner and in this particular showing, one end is threaded to engage in a threaded opening 12 provided in the base of the frame 10. Extending substantially parallel to the core member 11 is a support 13 which, in this instance, is formed integral with the base of the frame 10.

An armature 14 is mounted on the support 13 and disposed in alignment with the core member 11. In order to mount the armature for oscillatory movement, a notch may be provided at the end of the supporting member 13. In the construction illustrated, a notch 16 is provided by mounting on the support 13, a plate 15 which extends a short distance beyond the end of the latter.

The simplest type of armature that is suitable for this relay is a metal plate which is cut with a square end. In order to provide for oscillatory movement of the armature when mounted in the notch 16, provided between the end of the support 13 and the plate 15, it is necessary to space the walls defining the notch at an angle greater than a right angle. In this embodiment of the invention, in order to make the notch of the required angular extent, the plate 15 is bent upwardly at a point near the upper end of the support 13.

It will be readily understood that a sufficient angular movement of the armature may be obtained if the angle of the notch 16 is only slightly greater than the angle of the upper corner or knife edge 17 of the end of the armature 14 which seats in the notch. In practice, it has been found that it is sufficient to make the notch of an angular extent of from 5° to 7° greater than a right angle.

In order to mount the armature 14 so that it may be readily removed and replaced, a rectangular notch 18 is cut in the laterally extending plate 15. In cutting the notch, the plate is cut at two places to form a tongue

19 which is bent upwardly at an angle of about 45°. As shown, a plate 20 is mounted on the armature and provided with an extension or tongue 21 which extends through the notch 18.

5 The upper tongue 19 which is integral with plate 15 is provided with a slot 22 extending inwardly from the end for receiving a bolt 23, while the tongue 21 has an opening through 10 which the bolt extends. A spring 25 is mounted on the bolt 23 and is disposed to bias the armature 14 counterclockwise about the knife edge 17. In this manner, the armature is retained in position, the tongue 21 engaging 15 the sides of the notch 18 to prevent lateral movement, while the spring 25 biases it upwardly in the notch 16.

The armature may be readily removed by compressing the spring and forcing the bolt 20 upwardly to permit the moving of the armature laterally and the sliding of the bolt out of the slot 22.

As shown, the bolt 23 is provided with an adjustable nut 26 whereby any desired spring 25 tension may be applied to the armature. In this construction, a second support 27 is provided on the frame 10 which carries an L-shaped bracket 28, disposed to extend over the outer end of the armature 14. A set 30 screw 29 is mounted in the bracket and disposed in alignment with the armature to limit its angular movements. The set screw 29 may also be used as a contact member which, in conjunction with the armature 14, may 35 be utilized to perform switching operations.

The core 11 is provided with an armature receiving face 30. In this construction, the armature engages directly with the face 30.

In order to actuate the armature 14, a main 40 magnetizing coil 31 is mounted on the core member 11. As will be readily understood, this coil may be made from any desired number of turns of suitable conductor which will depend on the operating conditions to be met.

5 As shown, a neutralizing coil 32 is mounted 50 on the core 11 and may be connected to oppose the magnetizing action of the main coil 31. The size of the conductor and the number of turns provided in the coil 32 will depend upon the main actuating coil 31 and the manner in which it is desired to dissipate the residual magnetism that may be retained by the core 11 during the operation of the relay.

In the operation of the relay, the armature 55 14 may be actuated to the position illustrated, by the spring 25 only when the strength of the decaying flux becomes less than the biasing force of the spring. Generally, it is desirable to reduce the strength of the spring 60 to the minimum required in order to obtain fine adjustments as to time. However, such adjustments are difficult to make unless there is a fairly rapid or appreciable and continuous decay of lines of flux in the magnetic 65 circuit under which conditions, if the spring

is properly adjusted, the actuation of the armature will occur promptly and at a predetermined instant depending upon the biasing force.

It will be readily understood that when a 70 neutralizing coil 32 is provided, that after the energizing circuit of the main magnetizing coil 31 is interrupted, that the linkages tending to hold the armature 14 in contact with the face 30 of the core 11 may be substantially dissipated, permitting the actuation of the armature counterclockwise as viewed in Fig. 1 by a very light spring. In the structure shown, when the armature 14 is actuated counter-clockwise, the plate 20 75 mounted on the armature 14 is moved into engagement with the set screw 29.

80 Referring now to Fig. 3, a circuit is illustrated showing how the relay may be connected into a circuit. It will be observed that the neutralizing coil 32 is connected directly across the line conductors 33 and 34 and is continuously energized. The main actuating coil 31 is also connected across the line conductors 33 and 34 but has a circuit breaker 35 85 or other suitable switching means connected in series therewith. In order to provide for dissipating energy when the circuit is interrupted, a resistor 36 is connected in parallel with the actuating coil 31.

90 In this particular circuit, the load 37 is connected across the line in parallel with the coils 31 and 32. The contact members of the relay which are the armature 14 and the terminal 29, are shown connected directly in the load circuit, but it will be readily understood that in practice, they would probably be used to control an electromagnetic switch (not shown) which would, in turn, control the load circuit.

100 In order to explain the functioning and operation of the relay, reference will be made to the curves shown in Fig. 4 which illustrate the performance of the relay when provided with an air gap shim, without a shim and finally with a suitable neutralizing coil. The curves were plotted with flux densities as ordinates and time intervals as abscissae.

110 It will be noted that no shim is provided in this construction. However, the advantages of the present construction cannot readily be appreciated without making a comparison with the results obtained when the same relay is provided with a shim. The shim used in plotting the curve was carefully proportioned in order to obtain the longest time element possible with positive action.

115 When the relay was provided with an air gap shim, the flux decayed very rapidly upon the interruption of the magnetizing circuit through the main actuating coil 31, as shown by curve 38. As will be readily understood, the desired operation of the relay cannot be obtained with any certainty at a point beyond 120 125 130

the knee of the curve which is substantially indicated by the ordinate 39.

When the air gap shim was removed and the relay tested, a curve similar to 40 was obtained which indicates that the flux decayed 5 more gradually, but the residual magnetism was much greater. In this instance, the same spring tension will not effect the operation of the armature. The knee of the curve is 10 substantially the ordinate 41. While the relay without the air gap shim gives a greater time interval, yet the spring pressure required to actuate the relay is excessively high and 15 unsuited for continuous operation.

The relay when equipped with a neutralizing coil such as 32, gave a curve 42 in which the knee of the curve indicated by the point 20 43, is found to be much further along the abscissa and the residual magnetism is reduced to substantially zero. This shows that the time element is considerably increased.

In carrying out the test, the selected relay 25 was operated under similar conditions as to spring pressure and voltage. The time intervals indicated by the points 39, 41 and 43, were .52, 1.05 and 1.7 seconds, respectively.

From the above, it will be readily understood that the relay provided with a neutralizing coil gives a much more gradual decay 30 of flux, thereby increasing the time interval during which positive operation of the relay at a predetermined time may be obtained by the setting of the spring 25. Further, since the residual magnetism is reduced to substantially 35 zero, there is no possibility of the armature sticking, since the linkages are substantially all dissipated and the armature may be actuated by a comparatively weak spring.

Since certain changes may be made in the 40 above construction and different embodiments of the invention may be made without departing from the scope thereof, it is intended that all matter contained in the above description or shown in the accompanying drawing shall 45 be interpreted as illustrative and not in a limiting sense.

I claim as my invention:

1. In a relay in combination, a core member, an adjustable spring-biased armature disposed in alignment with the core member, a main coil for magnetizing the core member to effect the operation of the armature, an auxiliary coil disposed to dissipate the residual magnetism in the core member when the main coil is deenergized, thereby to increase the time during which the magnetism of the core dissipates at a rapid rate and the period of time during which positive functioning of the armature may be obtained at 55 any predetermined time interval.

2. In a relay in combination, a movably mounted armature, means for biasing the armature to predetermined positions, an electromagnet from which when deenergized the 60 lines of magnetic force dissipate rapidly

until substantially only the lines of magnetic force constituting the residual magnetism remain, said electromagnet being disposed to actuate the armature, an auxiliary coil associated with the electromagnet and disposed to dissipate the residual magnetism when the electromagnet is deenergized to give a continuous and rapid decay of the flux to permit the operation of the armature under the influence of the biasing means. 70

3. In a relay in combination, a movably mounted armature, means for biasing the armature to a predetermined position, an electromagnet from which the lines of magnetic force dissipate rapidly until substantially only the lines of magnetism constituting the residual magnetism remain when deenergized, said electromagnet being disposed to actuate the armature, an auxiliary coil for dissipating the residual magnetism of the electromagnet to increase the time during which lines of magnetic force are dissipated from the electromagnet with sufficient rapidity to permit the operation of the armature at any instant during the process of dissipation of flux, thereby to increase the time during which the positive functioning of the armature may be obtained in response to the biasing force of said biasing means. 80

4. In a relay in combination, a frame, a core member provided with an armature receiving face carried by the frame, an armature supporting member mounted on the frame, an armature disposed in alignment with the core member carried by the supporting member, said supporting member being provided with a notch for receiving an end of the armature, the end of the armature disposed in the notch being provided with a knife edge, the angular extent of the end of the armature about the knife edge being less than the angular spacing of the walls of the notch, thereby to permit oscillatory movement of the armature in the notch, means for biasing the armature to a predetermined position, said biasing means being disposed to retain the armature in position in the notch, a main energizing coil mounted on the core for drawing the armature into engagement with the core member, and an auxiliary coil for dissipating the residual magnetism when the main coil is deenergized, to permit said biasing means to actuate the armature out of engagement with the core. 95

5. In a relay, in combination, a movably mounted armature, adjustable means for biasing the armature to a predetermined position, an electromagnet for actuating the armature against the action of the biasing means, means for causing the lines of flux to dissipate rapidly and continuously to substantially zero upon the deenergization of the electromagnet thereby to permit the positive and prompt operation of the armature at a predetermined 100 110 115 120 125 130

instant depending upon the adjustment of the biasing means.

6. In a relay, in combination, a movably mounted armature, adjustable spring means for biasing the armature to a predetermined position, an electromagnet disposed to generate flux for actuating the armature against the action of the biasing means, an auxiliary coil associated with the electromagnet for dissipating the flux rapidly and continuously to substantially zero upon the deenergization of the electromagnet thereby to permit the positive and prompt operation of the armature at a predetermined instant depending upon the adjustment of the biasing means.

7. In a relay, in combination, a core member, a spring biased armature in alignment with the core member, means for varying the biasing force applied to the armature, a main coil for magnetizing the core member to effect the operation of the armature, an auxiliary coil disposed to effect a substantially constant dissipation of the residual magnetism of the core from the maximum energized condition to zero, thereby to obtain a prompt action of the armature at any predetermined time during the process of the dissipation of the residual magnetism in response to adjustments of the means for varying the biasing force applied to the armature.

8. In a relay, in combination, a core member, a spring biased armature disposed in alignment with the core member, a spring for biasing the armature to a predetermined position, means for varying the biasing force of the spring, a main coil for magnetizing the coil member to effect the operation of the armature, an auxiliary coil disposed to effect a substantially constant dissipation of the residual magnetism of the core from the maximum energized condition to zero, thereby to obtain a prompt action of the armature at any predetermined time during the process of dissipation of the residual magnetism, in response to adjustments of the means for varying the biasing force of the spring that is applied to the armature.

In testimony whereof, I have hereunto subscribed my name this first day of September, 50 1928.

WILLARD G. COOK.
